CORELESS OPERATING CABLE

Charles M. Zerr, Independence, Mo., assignor to
 Union Wire Rope Corporation, Kansas City,
 Mo., a corporation of Missouri

Application March 8, 1948, Serial No. 13,580

4 Claims. (Cl. 57—139)

1

This invention relates to the fabrication and construction of operating cables, it being understood by "cable" as meaning composite structures such as moving, hoisting or stationary bridge cables and composed of straight, stranded or twisted elements bound together to form a unit and produced from metallic substances.

Such cables are conventionally formed in a number of various ways, but usually consist of a number of stranded wire ropes, each consisting of a number of strands made from a plurality of metal wires, laid or helically bent around a suitable core member.

To those skilled in the art, cable construction and variances in combinations of its component elements have come to mean the number and arrangement of the ropes and strands thereof and the number, size and arrangement of the wires in the strands. Heretofore a generally uniform pattern has been followed and consisted of bending the wires helically in one or more layers around a core wire to form a strand. These strands were then similarly laid around a "center" or core made of hempen fiber of various grades, of an independent wire rope core, or a stranded core. The wire rope thus formed was then similarly laid about a suitable "heat" or core.

It is the most important object of this invention therefore, to provide an operating cable wherein the usual core about which the wire ropes are laid is eliminated and where the core for the individual wire ropes about which the strands are laid is also omitted.

The primary aim of this invention therefore, is to provide an operating cable made from a number of wire ropes, each made of a number of strands, and the strands themselves being formed from any number of wires.

Other objects of this invention are to provide an operating cable that has a high degree of flexibility as compared with the conventional wire cable; that is extremely resistant to crushing; that is capable of production from relatively larger individual wires to more effectively withstand surface wear; and that cannot become damaged from kinking.

Other objects and aims will become apparent during the course of the following specification reference being had to the accompanying drawings, wherein:

Fig. 1 is a fragmentary perspective view of a coreless operating cable made in accordance with the present invention.

2

Fig. 2 is a transverse cross sectional view taken on line II—II of Fig. 1.

Fig. 3 is a cross sectional view taken on line III—III of Fig. 1.

Fig. 4 is a cross sectional view similar to that shown in Fig. 2 but showing a modified view of my present invention.

Fig. 5 is a cross sectional view similar to that shown in Fig. 2 showing another modified form of the invention; and

Fig. 6 is a cross-sectional view like that of Fig. 2 showing another modification thereof.

This operating cable is broadly designated by the numeral 10 and made from a plurality of wire ropes 12, there being three shown in Figs. 1 to 3 inclusive of the drawing. It is notable that any of well known lays may be used in strands the ropes 12 in lieu of that illustrated without departing from the broad principles herein intended.

Each of the wire ropes 12 is composed of three strands 14 suitably laid and using conventional helicoidal constructions, and each of these strands 14 is produced by helically bending a number of wires 16 in the usual manner.

The wires 16 are helically laid together around a core wire in a symmetrical position to form the unitary strands 14, the number of wires 16 varying from three to several score if desired. The ropes 12 however, are coreless, the strands 14 being simply laid about the longitudinal axis of each rope 12, and the ropes 12 are laid about the longitudinal axis of cable 10 without the use of a core.

From the foregoing it readily becomes apparent that a cable has been developed that is far superior in many ways to those commonly produced. The life of a wire rope or of the cable made therefrom, is influenced directly by the

life of its core. In the case of help fibers of vegetal origin, rapid physical and chemical deterioration takes place particularly when subjected to rotting and other deteriorating elements.

Furthermore, axial pulls and bending stresses upon the core have great effects on cores and tend to lessen the life of the cable appreciably.

Although the core of a wire rope has been heretofore deemed necessary and serves as a bearing for the strands laid about it, many disadvantages arise from its use.

In the first place, when a core is used, the cable formed is much less flexible than the cable 10 herein specified. Commercial requirements 55 of operating cables call for one that will easily

pass over small sheaves and also capable of short reverse bends in complicated machines and implements.

Secondly, cores are easily crushed and smashed out flatly when the cable is placed in strenuous use. Actually, such cores become elliptical in cross section and usually pass between adjacent strands of the rope when wear commences. When such core finally breaks, the cable is virtually incapable of further use. Elimination of the 10 cores solves these problems.

A third advantage of the present cable lies in its abrasive resistance. By omission of the cores, the individual wires 16 can be appreciably larger in cross sectional diameter without producing a large, bulky cable than would result from use of such large wires in the conventional cable. Obviously, surface wear becomes much less damaging when the wires 16 themselves have more wearing area.

Kinking is a fourth primary problem in usual types of cables. Kinks cannot be successfully removed and once such condition exists the cable becomes permanently damaged. Cable 10 above described can be kinked to the extent of actually tying knots thereto and such kinks easily removed without damage thereto.

For many uses therefore, the operating cable forming the subject matter of this invention has many advantages. Typical examples are slings, excavating machinery, concreting machinery, derricks, tackles, clam-shell buckets, power shovels and the like. Many types of clam-shell buckets for instance have relatively small sheaves over which the cable must pass, requiring high 35 flexibility. Also, machines having long booms present surfaces against which the cable continually "slaps" and "pounds," causing surface damage referred to in the trade as "peening." Because of the formation of cable 10 as above described, such abrasive wear does not shorten the life thereof as quickly as in conventional cables.

Figs. 2 and 3 of the drawing illustrate but two of the many possible views when sections are taken transversely through the cable 10. These views illustrate how it is possible to attain symmetry though no core is used and show how, in this type of 3 x 3 cable, no support is needed either for the strands 14 or the ropes 12. The other function of a core i. e. as a bearing, is not needed, since the surface wear of a cable is usually more important and causes break-down before wear due to rubbing together of individual strands.

In Fig. 4, a cable 100 is illustrated in section only, showing a number of individual stranded wires 102, forming strands 104, the latter of which are laid together to present ropes 106. In this case, three ropes 106 are used to form cable 100 and each rope 106 has two strands 104.

In Fig. 5, a cable 200 comprises three ropes 202, each made up of four strands 204, which in turn are formed by stranding a number of wires 206.

Fig. 6 illustrates the same broad principle above outlined, but showing a cable 300 having

four ropes 302. These ropes 300 include two strands 304 each and strand 304 have a number of wires 306 forming the same.

Thus, illustrations have been made of a 3 x 3 cable, a 3 x 2 cable, a 3 x 4 cable and a 4 x 2 cable. Other possible combinations include a cable having two ropes with two, three or four strands each; and four ropes with three or four strands each. In each case, there is no necessity for a core since the supporting function thereof is not needed and the many advantages set forth above by its omission, will result.

Having thus described the invention, what is claimed as new and desired to be secured by Letters Patent is:

1. An operating cable of the character described comprising a plurality of identical elements bound together to form a composite, elongated unit, said elements being stranded about the longitudinal axis of said unit, said axis being coreless, said elements each comprising a number of wire ropes.

2. An operating cable of the character described comprising a plurality of elements bound together to form a composite, elongated unit, said elements being stranded about the longitudinal axis of said unit, said elements each comprising a number of wire ropes, said ropes each comprising a plurality of identical, coreless strands helically laid about the longitudinal axis thereof.

3. An operating cable of the character described comprising a plurality of elements bound together to form a composite, elongated coreless unit, said elements being stranded about the longitudinal axis of said unit, said elements each comprising a number of wire ropes, said ropes each comprising a plurality of strands helically laid about the longitudinal axis thereof, said strands each comprising a number of helically bent wires.

4. An operating cable of the character described comprising a composite, coreless unit having a plurality of helically laid wire ropes, said ropes each being coreless and comprising a number of helically laid strands, said strands each comprising a plurality of stranded wires.
